UNITED STATES PATENT OFFICE.

STEPHEN F. NAUGHTON, OF THE UNITED STATES NAVY.

MONOPLANE.

1,176,593.

Specification of Letters Patent. Patented Mar. 21, 1916.

Application filed February 12, 1915. Serial No. 7,890.

To all whom it may concern:

Be it known that I, STEPHEN F. NAUGHTON, of the United States Navy, a citizen of the United States, residing at New York, in the county of New York, and State of New York, have invented new and useful Improvements in Monoplanes, of which the following is a specification.

This invention relates to monoplanes, and 10 its object is to provide structural features increasing the strength, durability and general efficiency of this class of air craft.

The invention is illustrated in the accompanying drawings, in which:—

15 Figure 1 is a side elevation of my improved monoplane. Fig. 2 is a front elevation of the same. Fig. 3 is a top plan view, partially broken away. Fig. 4 is a vertical transverse section through the fuselage. 20 Fig. 5 is a view of the control device. Fig. 6 is a sectional side elevation of a portion of the landing gear. Fig. 7 is an enlarged detail view, partly in section, showing a bracing construction. Figs. 8 and 9 are 25 tail views of clips or guy wire connections. Fig. 10 is a sectional view taken substantially on the line 10—10 of Fig. 9.

Referring to the drawing, 1 designates the body of the machine, which is of stream 30 line form, and provided with a cock pit or compartment 2 to receive the motor and aviator and one or more passengers. The body has an empennage or tail extensions 3 carrying fixed vertical stability fins 4 and 35 fixed horizontal stability fins 5. Hinged or pivoted to the rear end of the body in line with the vertical fins is a vertical rudder 6, and hinged or pivoted to the rear edges of the horizontal fins are the sections 7 of a 40 double or two-part horizontal rudder, which rudders are controlled by a steering gear located within the body as hereinafter fully described.

The body is constructed of a suitable frame 45 work over which is placed a covering of metal, fabric or other suitable material. This frame work includes longitudinal spars 50 connected by suitable vertical and horizontal struts or cross pieces 9, the frame work being reinforced by stays 10. The stays 10 are secured to and extend from suitable clips or brackets fastened between the longitudinal spars and struts or cross pieces, which braces may be of the three-arm type 55 designated by 11 in Fig. 8 or the four-arm type designated by 12 in Fig. 9, according

to position and the number of stays and struts employed, each bracket having an opening 13 for the passage of a dowel or fastening bolt 14 connecting the same with 60 the strut to the longitudinal spar, as shown in Fig. 7, the arms of the bracket being arranged at proper angles and apertured for the reception of the ends of the stays which are suitably tied or otherwise fastened thereto. By this construction, and by 65 the use of other proper bracing at desired points when required, a strong and durable type of stream line body is provided.

The supporting surface of the machine 70 comprises a plane composed of laterally extending wings 15 fastened at their inner ends to the body and reinforced from the body and from each other by upper and lower braces 16 engaging suitable anchor 75 staffs or brackets 17. The wings may be of any ordinary or preferred general structure and curvature and are provided with adjustable tips or ailerons 18. These tips or ailerons are connected above the plane 80 for movement in unison by a cord or cable 19 extending over suitable guide pulleys 20, and said tips or ailerons are respectively attached below the plane to cables or cords 21 and 22 passing over suitable guide pulleys 23 to a point within the cock pit, where 85 they are connected with a control device as hereinafter described. It will be observed that the tips are coupled for movement in unison, one moving upwardly while the other moves downwardly, and that said tips are 90 separated from the wings along the diagonal division lines 24 to swing on oblique rearwardly converging axes, so that when the tip at the low side of the unbalanced 95 machine is depressed for a lifting action it will also assume an angular position to the line of flight which diminishes the resistance of the wing and top to forward travel. On the other hand, the wing at the 100 high side which is swung upwardly to depress that side will be shifted at such an angle to the line of flight as to increase the resistance of said wing to forward travel thus preventing the high side from traveling 105 at a faster rate of speed than the low side and avoiding fore-and-aft oscillation of the machine on its vertical axis during balancing or banking operations.

Arranged within the forward portion of 110 the body 1 is a driving motor 25 which communicates motion to a forward or tractor

propeller 26. The motor shown in the present instance is of the water-cooled type, and its water jacket 27 is connected by flow pipes or tubes 28 with radiators 29 at the opposite sides of the body. These radiators are provided with laterally extending vanes or ribs 30, which project outwardly through discharge openings 30' in the sides of the body and operate in the forward travel of the machine to produce a partial vacuum or suction, whereby a draft of cooling air is drawn inwardly through a suction opening 31 in the bow of the body and discharged through the openings 30'. Within this opening 31 is a spider or skeleton bearing 32 in which the propeller shaft is journaled. The vanes 30 lie in the path of the air from the propeller so that their suction producing action is increased to a material degree.

20 The means for adjusting and controlling the rudder and wing tips comprises a lever 33 pivoted to swing laterally at its lower end on a pivot member 34 on which are loosely journaled guide or direction pulleys 35 and 36. At its upper end the lever is provided with a bearing 37 for a shaft 38 provided with a hand wheel 39 and a drum or pulley 40. Attached to the lever at the point 41 are the forward ends of cables 42 which pass rearwardly over suitable guides and are coupled to the rudder 6 whereby the latter may be adjusted through lateral movements of the lever 33 on its axis 34. The inner ends of the cords or cables 22 pass around the pulleys 35 and 36 and are arranged to wind in opposite directions about the drum 40, whereby the ailerons 18 may be adjusted in an obvious manner. A second lever 43 is arranged within the cock pit and is coupled by a suitable connection or connections 44 with the horizontal rudder members 7 whereby the same may be adjusted.

45 The machine embodies a landing gear of improved construction including front cushioned wheels 44 and skids or runners 45 and a rear skid or fender 46. The skids or runners 45 are arranged at the opposite sides of the fore-part of the body and are rigidly connected therewith by bracket rods 50 or tubes 47 and reinforced by braces 48. The wheels 44 are arranged in pairs at opposite sides of the body, each pair being carried by a wheel support consisting of a triple fork 49, the arms of which support 55 a transverse axle pin 50 on which the wheels 44 are mounted within the outer fork spaces. Journaled upon the axle within the middle fork space is a friction wheel or roller 51 over which passes a rubber or other elastic band 52 secured in front and rear of said friction wheel to the skid 45. As shown, the skids extend beneath the friction wheels or spools 51 which are held between the skids and

65 the elastic bands 52, whereby the fork 49 and wheels 44 are permitted to have vertical movement relative to the skids and are given a resultant cushioning action through the elasticity of the rubber backing bands 52. Each fork 49 has an upwardly extending guide stem 53 which is movable vertically within a guide tube or sleeve 54 fixed to the adjacent side of the body. Inclosed within the body is a coiled cushioning spring 55 backing the stem 53 and sustaining the sleeve therefrom, and inclosing the outer portions of the stem and sleeve is a cushioning spring 56 bearing against abutment shoulders 57 and 58, by which additional cushioning means are provided for sustaining and cushioning the weight of the machine in launching and landing actions and in traveling over rough ground surfaces. It will be observed that the described construction not only provides a cushioning connection between the wheels and skids, but also between the wheels and body, giving a maximum cushioning action.

70 80 85

It will be evident from the foregoing that my invention provides a monoplane which, while simple of construction, embodies points of superiority in various respects, including means for securing an exhaust of the hot air from the motor compartment, means for balancing and banking the machine with efficiency and means for securing a cushioning action which has a high range of flexibility and capacity to resist strains without damage.

90 95

90 100 105 110 115 120

I claim:—

In a flying machine, the combination of a hollow body or nacelle having a suction opening in the front portion and sets of discharge openings in the side portions of its bow, a supporting surface carried by the body, suitable steering and stabilizing means, a motor positioned in the bow of the body and having its shaft extending forwardly through the suction opening, radiators at the sides of the bow of the body having suction producing vanes projecting outwardly through said discharge openings, so as to lie in the path of the wind and directly in the path of the air from the propeller, whereby a suction is produced within the bow to draw cooling drafts of air thereinto through the suction opening and discharge the same through the said side discharge openings, and conductors extending between and connecting the radiators with the water jacket of the motor.

100 105 110 115 120

In testimony whereof I affix my signature in presence of two witnesses.

STEPHEN F. NAUGHTON.
